PATRICK J. HENRY, OF BURLINGTON, VERMONT, ASSIGNOR, BY MESNE ASSIGNMENTS,
TO AUTO LICENSE HOLDER CO., INC.

AUTOMOBILE-BOX FASTENER.

1,322,188.

Specification of Letters Patent.

Patented Nov. 18, 1919.

Application filed July 26, 1918. Serial No. 246,913.

To all whom it may concern:

Be it known that I, PATRICK J. HENRY, a citizen of the United States, residing at Burlington, in the county of Chittenden and 5 State of Vermont, have invented new and useful Improvements in Automobile-Box Fasteners, of which the following is a specification.

This invention relates to receptacles especially adapted for use in motor or other vehicles and is designed to hold cards, operators' licenses, etc., in a convenient place so as to be readily accessible at all times.

The primary object of the invention is the 15 provision of a receptacle having a plurality of separate pockets open at their top and one side so as to permit of the ready removal or insertion of the contents, each of said pockets being carried by separate sections hinged 20 together and provided with spring flanges so that they may be folded one against the other and frictionally held in such position, one of such sections carrying a cover which is adapted to form a closure for the open 25 ends of both of the pockets.

Another object of the invention is to provide a receptacle of this class which is neat and attractive in appearance, simple of construction and capable of being easily attached in position and when so attached will provide a convenient receptacle for the above and other purposes.

With these and other objects in view the invention consists of the following novel 35 combination and arrangement of parts hereinafter more fully described, illustrated in the accompanying drawings and specifically pointed out in the appended claims.

In the drawings,

40 Figure 1 is a perspective view of the receptacle in its closed position;

Fig. 2 is a similar view of the receptacle open;

Fig. 3 is a transverse sectional view in 45 position shown in Fig. 1; and

Fig. 4 is a longitudinal sectional view of the same.

In the use of motor vehicles, the operator is often without his license or registration 50 card owing to no convenient place being provided for keeping the same with him and is therefore subject to annoyance or fine by the authorities. It is for the purpose of

overcoming this disadvantage that the following invention is provided. 55

In the drawings, there is illustrated a receptacle which includes a pair of members which are adapted to be folded one upon the other to form a closed receptacle. One of these members 10 is in the form of a stationary member, in that it is adapted to be secured to the instrument board or any other convenient place within the vehicle by means of the flanges 11, which are provided with apertures 12 for the reception of screws or 60 other fastening devices. The stationary member 10 is provided with inturned longitudinal flanges 13 and a transverse flange 14, which are spaced from the body portion of the member to provide a pocket 15, which is 65 open at its side and one end and is designed to receive the license or registration card of the operator.

Spaced from the flange 14 is a laterally extending spacing flange 16, to which is 70 hingedly secured as shown at 17 a hinged member 18. This latter member is also provided with spaced longitudinal flanges 19 and a transverse flange 20, to provide a 75 pocket 21 similar to the pocket 15. 80

When the receptacle is in its closed position the flanges 13, 14 and 19, 20 are adapted to abut, so as to close the sides of the pockets 15, 21, the ends of the said pockets being closed by means of a hinged closure 85 22, which is secured to the member 18 by a hinge 23, the said closure being co-extensive in width to the flange 16 so as to extend over both of the pockets.

In order to hold the receptacle in its folded or closed position, the member 18 is provided with longitudinal spring side members 24, which are adapted to engage longitudinal edges of the stationary member, and to be held in such engagement through the 90 frictional action caused by the resiliency of these side members. The said member 18 is provided with an operating knob 25, which is located adjacent the hinged closure 22 so as to be conveniently grasped. 95 100

While the device is especially adapted for the uses set forth, it may be conveniently used for other purposes, such as shopping memorandum and the like, its manner of operating permitting of ready access to the 105 interior thereof, so that the said memoran-

dum may be conveniently read without removal.

Having described the invention, what is claimed is:

5. 1. A receptacle comprising a pair of hinged members adapted to be folded one against the other, an open ended pocket provided in each of said members, a common closure for both of said pockets and means 10 for retaining said members in their folded position.

2. A receptacle comprising a stationary member, spaced flanges secured thereto to form an open ended pocket, a hinged member 15 secured to said stationary member spaced flanges secured to said hinged member to form a second open ended pocket, a common closure for both of said pockets and spring flanges carried by one of said 20 members and extending beyond its pocket for holding the receptacle in closed position.

3. A receptacle comprising a stationary member, spaced flanges secured thereto to 25 form an open ended pocket, a hinged member secured to said stationary member and adapted to be folded against the same, spaced flanges secured to said hinged member to form a second open ended pocket, a

common closure for both of said pockets, 30 and frictional means for retaining said members in folded position.

4. A receptacle comprising a pair of elongated members, having their ends hingedly secured together and adapted to be 35 folded one against the other, a pocket provided on the opposed faces of each of said members, said pockets being open at their ends remote from the hinge and a hinged closure carried by one member and adapted 40 to be folded over the open ends of both pockets.

5. A receptacle comprising a pair of elongated members having their ends hingedly secured together and adapted to be 45 folded one against the other, inwardly extending longitudinally disposed flanges located along the edges of each of said sections and spaced from the opposed faces thereof to provide pockets, said flanges being adapted 50 to contact when the receptacle is closed and laterally extending longitudinally disposed spring flanges projecting beyond the inwardly extending flanges of one section for frictional engagement with the inwardly 55 extending flanges of the other section.

In testimony whereof I affix my signature.
PATRICK J. HENRY.
